[57] ABSTRACT

For special applications modifications of the sweetness intensity or the taste characteristics of the new non-nutritive sweetener Acesulfame K may be required. The taste of Acesulfame K can be modified using mixtures with magnesium sulphate, sodium glutamate, disodium inosinate, disodium guanylate, quinine sulphate, maltol, ethyl maltol, 2,5-dimethyl-3-hydroxy-4-oxo-4,5-dihydrofuran, or thaumatin alone or in suitable combinations, in which Acesulfame K is the main ingredient. These mixtures may be used instead of pure Acesulfame

K in the following preparations. For preparing granules, powders, tablets, or solutions Acesulfame K can be mixed with potassium chloride, potassiumdihydrogen phosphate, potassium acetate, potassium hydrogen tartrate, disodium hydrogenphosphate, trisodium citrate glucono- δ -lactone, starch syrups of low DE (=Dextrose Equivalent) values, low-viscosity carboxymethyl cellulose, and gumarabic alone or in suitable combinations. A dilution of Acesulfame K to low sweetness intensities is possible using calcium chloride, tricalcium phosphate, calcium lactate, calcium gluconate, potassium hydrogen carbonate, potassium chloride, potassium polyphosphate potassium hydrogen tartrate, sodium chloride, trisodium phosphate, disodium hydrogenphosphate, sodium gluconate, glycin, fumaric acid, citric acid, malic acid, tartaric acid, glucono- δ lacton, glucose, fructose, maltose, lactose, sorbitol, starch syrups having low to medium DE-values, gum arabic, hydrolyzed soluble casein, and soluble gelatin. The taste of the mixtures was rated superior or equivalent to the pure Acesulfame K.
